METHOD OF AND MEANS FOR PRODUCING
TEXTILE FABRICS

Oskar Sauer, Philadelphia, Pa.

Application May 16, 1935, Serial No. 21,709

35 Claims. (Cl. 66—85)

This invention relates generally to textile fabrics and, more particularly, to the production of an improved fabric of the porous or net type, as well as to laces and curtains. Porous and net type fabrics, when produced as heretofore on looms, have the disadvantage that the warp threads or yarns will slide along the weft thread or yarn with the result that the fabric opens up.

The general object of this invention is to obviate the noted disadvantage by provision of a novel method and means whereby the warp threads or yarns are twisted about the weft thread or yarn, or about one another at the crossovers, in a manner which effectively prevents sliding of the one relative to the other.

Another object is to produce a fabric of the above indicated character which is stable in texture and of great durability.

A further object is the production of lace or net fabric in which the interlacings are only formed when one of the constituent threads or yarns is thrown laterally relative to the other or others.

Ancillary objects and advantages of this invention will be pointed out in the detailed description thereof which follows, or will be apparent from such description.

With the foregoing objects in view, this invention aims to produce a more open fabric of the indicated types, in which a chain of one or more warp loops is introduced and the chain threads or yarns interlaced with them by lateral throwing, as well as with the weft threads or yarns at the crossovers, by throwing one or more loops around them. The chain threads or yarns may also be thrown laterally two or more gaits, and the loops formed by the interlacing thread or yarn will form the points of interlacing, thus various patterns may be easily designed. This novel manner of interlacing differs from knitted fabrics, wherein one loop engages another loop and an elastic fabric results. The chain of warp loops or the interlacing threads or yarns, form only points of interlacing and the stability of the fabric is carried by said chain as well as by the weft threads or yarns. The novel principle of forming points of interlacing by a chain of loops, either in front or at the back of the fabric, or both, is also intended to eliminate use of the conventional bobbins employed in all types of lace and curtain looms, and thereby dispensing with the costly method of "refilling", with a limited quantity of thread or yarn, the thousands of wafer-like bobbins by substituting, for said bob-

bins, spools or beams of the desired threads or yarns.

To the foregoing ends, and in accordance with this invention, the warp threads or yarns, held by various numbers of guide bars, are thrown laterally one or more gaits in a predetermined manner and direction according to the pattern desired, whereupon interlacing points are formed with appropriate means by drawing or pulling a loop from an interlacing warp thread or yarn at the opposite side of the fabric and throwing the warp threads or yarns laterally.

In order to produce certain types of fabric, where threads or yarns float in a predetermined manner on the face of the fabric, the interlacing thread or yarn is supplied at the back of the fabric, and a loop is pushed or pulled to the front thereof, where it is held until the warp thread or yarn has been thrown laterally and beaten-up, whereupon said loop is drawn to the rear through the warp threads or yarns at right angles to the fabric and tied around the previous laterally-thrown warp threads. The warp threads are thrown laterally again and beaten-up, this time, however, relatively in front of the interlacing loops, which are being held in the rear of the fabric, and consequently it will be floated across the face of the fabric. When the warp threads or yarns do not move, as aforesaid, they cannot tie-in after any motion, thus after a predetermined manner, thread or yarn can be floated on the fabric every one or more motions.

In order that this invention may be clearly understood, and its advantages fully appreciated, reference will now be had to the accompanying sheets of drawings depicting convenient means for carrying out the fundamentals of said invention.

In the drawings:

Fig. I is a fragmentary cross-section through a loom adapted for carrying out one manner of producing porous or net fabric in accordance with this invention, said section being taken approximately as indicated by the arrows I—I in Fig. V.

Fig. II is a similar view, taken as indicated by the arrows II—II in Fig. VII.

Fig. III is a corresponding view illustrative of a stage in the beating-up of the interlacings towards the fabric.

Fig. IV is a cross-section, taken as indicated by the arrows IV—IV in Fig. VIII.

Fig. V is a plan view corresponding substantially with the arrangement of the weaving elements shown in Fig. I.

Fig. VI is a plan view similar to Fig. V, but showing the position of the sinkers after lateral movement preparatory to forming the sheds.

Fig. VII is a plan view of the elements shown in Fig. II, or the position occupied thereby, incident to shed formation.

Fig. VIII is a plan view of Fig. IV.

Fig. IX is a fragmentary perspective view of the weaving elements shown in Fig. I. 10 Fig. X is a similar view, conformable to the showing of Fig. II.

Fig. XI is a fragmentary cross-section, taken on the plane XI—XI of Fig. XIV, through a loom adapted to the production of a lace or net fabric 15 in which two warp threads or yarns are employed, one being interlaced with the weft thread or yarn by looping and the other by formation of chain stitches.

Fig. XII is a similar cross-section, taken on the plane designated XII—XII in Fig. XV, and showing how the chain stitches are caused to interlace the looping warp yarn.

Fig. XIII is a similar view showing how the shed is formed, said section being taken on the 25 plane designated XIII—XIII in Fig. XVIII.

Fig. XIV is a plan view conformable with Fig. XI.

Fig. XV is a similar view conformable with Fig. XII, but showing how the chain stitch warp 30 thread or yarn is interlaced with the looping warp thread or yarn.

Fig. XVI is a similar plan view to Fig. XV, but showing how the looping warp thread or yarn may be interlaced with the chain warp in the 35 opposite direction.

Fig. XVII is a plan view showing the shed forming means after a lateral movement preparatory to forming the sheds.

Fig. XVIII is a similar view to the preceding 40 figure, but showing the shed forming means in descended position.

Fig. XIX is a like view showing the shed forming means in the normal or initial position, with the weft yarn beaten-up.

45 Figs. XX and XXa are, respectively, a cross-section and side view of the novel weaving means as adapted for the production of a fabric in which one warp thread or yarn is floated across the fabric in one direction, and interlaced with another, and the weft thread or yarn in the reverse direction.

Figs. XXI and XXIa are views, corresponding to Figs. XX and XXa, but showing how new loops of one of the warp threads are drawn through 55 previously formed loops thereof, while the other warp threads or yarns are floated in front of the fabric.

Figs. XXII and XXIIa, as well as XXIII and XXIIIa, are views similar to the four immediately preceding ones, but illustrating how the warp thread or yarn is caused to interlace with the loops of the weft thread or yarn.

Figs. XXIV and XXIVa, as well as XXV and XXVa, are views similar to Figs. XX—XXIa, 65 showing the manner of producing a fabric in which one of the warp threads or yarns is interlaced in both directions.

Fig. XXVI is a diagrammatic view of a piece of fabric woven in accordance with this invention and in which double chains are formed of the weft yarn.

Figs. XXVII, XXVIII, XXIX and XXX are cross-sections showing how the various elements, in accordance with this invention, successively 70 coact to produce the fabric shown in Fig. XXVI.

Referring more in detail first to Figs. I—X, inclusive, the reference numeral 1 designates a stationary member or rail having projecting warp guide-fingers 2, with intervening loop-forming instrumentalities 3; while 4 comprehensively indicates the movable reed. Each guide finger 2 is provided with a base or main-warp guide-eye 5, and, at its free end, with a notch 6 for a purpose later on explained.

Suitably mounted with capacity for lateral and vertical reciprocation, in respect to the guide fingers 2 and loop-forming instrumentalities 3, is a shedding means which includes parallel bars 7, 8, respectively affording dependent-support for binder-warp guide-fingers or heddles 9 and loop-drawing instrumentalities 10. Each heddle 9 is provided with a binder-warp guide-eye 11, and each loop-forming instrumentality 10 with a notch 12 at its free end; while intermediate the loop-forming instrumentalities 10 and supported from the bar 8 are comb-members or fingers 13 having their lower ends concaved, or otherwise suitably shaped, at 14 for a purpose hereinafter set forth.

Having briefly described the various instrumentalities illustrated in Figs. I—X, inclusive, it is to be noted that alternating main and binder warp threads or yarns 15, 16, respectively, are supplied thereto from spools or beams, not shown. Each main-warp thread or yarn 15 is preferably drawn below the stationary rail 1, from its source of supply, through the eye 5 of an associated guide finger 2 to the point of crossover or interlacing with the weft thread 17. Somewhat similarly, each binder-warp thread or yarn 16 is preferably drawn over the top of the stationary rail 1, from its source of supply, through the guide-eye 11 of an associated heddle 9 and over the adjacent loop-forming instrumentality 3 to the point of interlacing with the main warp and 40 weft threads or yarns 15, 17.

In accordance with the form of the invention just described, the manner of forming the points of and effecting the interlacing or knit-weaving of the respective threads or yarns 15, 16 and 17, 45 at the crossovers is as follows:

Assuming the various instrumentalities occupy the respective positions indicated in Fig. V, relative to the fabric F, after the immediately-preceding knit-weave or interlacings have been 50 beaten-up by the reed 4, the bars 7, 8, while elevated as in Fig. I, are first moved laterally from the position shown in Fig. V to that of Fig. VI, with corresponding transfer of the heddles 9, 55 shed-forming instrumentalities 10 and fingers 13, for the distance of one gait, or approximately that intervening the respective main warps 15, with incidental laying of the binder warps 16 across the free ends of the loop-forming instrumentalities 3 and in the notches 6 of the guide-fingers 2. The shedding means including the heddles 9, loop-forming instrumentalities 10 and fingers 13, are next moved, by appropriate means, not shown, from the position indicated in Fig. VI to that of Fig. VII, to form the shed S, Figs. 60 II and X, through which the weft thread or yarn 17 is thrown by a shuttle or other suitable means. In forming the shed S, it is to be observed that the bar 8 carrying the loop-forming instrumentalities 10 and fingers 13 moves downwards, followed by the bar 7 carrying the heddles 9, with incidental drawing of loops from the main warp 15 and loops of the binder warp 16 by the fingers 13, through which the weft 17 is thrown to effect the knit-weave or interlacing of said warps and 75

weft at the crossovers, as will be clearly understood from Figs. V-VII, more particularly. The bars 1, 8 are then elevated and moved back to the position of Fig. V, with concurrent beating-up of the interlacings L against the fabric F by the reed 4, as depicted in Fig. VIII. It will thus be seen that the binder warp 16 is interlaced with the main warp 15 and weft 17 at their point of crossover, while said binder warp is floated diagonally between the points of interlacing L alternately in opposite directions. It will also be readily understood that fabric F may be produced with the means described by a one gait motion in one direction and a reversal; or, such fabric may be produced by a two or more gait motions in one direction followed by corresponding motions in the reverse direction, according to the degree of openness and pattern desired.

Referring now to Figs. XI-XIX, inclusive, which depict a modified means and manner of producing fabric in accordance with this invention, characterized by chain loops formed of one warp thread or yarn, all elements and parts corresponding to those previously described have like reference characters applied thereto with an added exponent a, in order to avoid unnecessary repetitive explanatory matter. Primary, the differing elements comprise the showing of a fabric-supporting bed or beam 18, and the structural addition of a needle-bar 19, a stationary sinker bar 20, and a reciprocative or otherwise movable comb 21; whereby, at each lateral motion of the heddles 9a and loop-forming instrumentalities 10a, the binder warp 16a is tied in, the needles 22 of the needle-bar 19 operating to pierce the fabric F^a and catch the main warp 15a at the back of the fabric F^a or vice versa, as desired; beard needles with presser edges being preferably employed for the finer gage threads or yarns, and latch needles for the coarser grades of thread or yarn.

Assuming now that the various parts or cooperating instrumentalities occupy the respective positions shown in Figs. XI and XIV, or, when the reed 4a is finally beating up the previously formed interlacings L^a with the comb 21 projected into position at the back of the weft thread or yarn 17a, by suitable means not shown, to prevent back movement of the fabric F^a, the reed 4a recedes to the position of Fig. XII. Concurrent with such recession of the reed 4a, the heddles 9a move laterally and descend, while the loop-forming instrumentalities 10a remain stationary. The comb bar 21 then moves from the position of Fig. XI to that of Fig. XII, and the needles 22 of the needle bar 19 advance to catch or draw new loops 23, Figs. XII and XV, of the main warp 15a, with subsequent "casting" or knocking-off of the stitches 24, previously held thereby, by the sinker-bar 20, as will be readily understood by those conversant with the art. The heddles 9a are now moved in the opposite direction laterally and descend, Fig. XVI, while the needles 22 are advanced to draw new stitches of the main warps 15a, and so tie in the interlacing or binder warps 16a at the crossovers. The heddles 9a and loop-forming instrumentalities 10a move laterally in the first explained direction, Fig. XVII, and thereupon descend to form the shed S^a, Figs. XIII and XVIII, as before described. The weft thread or yarn 17a is now thrown through the shed S^a while the loop-forming instrumentalities 10a recede, followed by the heddles 9a, to the starting position above the reed 4a, as indicated in Fig. XI, for passage of said reed forwards.

The reed 4a beats up to a position just in advance of the downward starting point for the heddles 9a and below that of the loop-forming instrumentalities 10a; while it is to be observed that the needles 22 with previously formed stitches 24 on their shanks move through the sinker-bar 20, to draw fresh loops 23 from the main thread or yarn 15a and cast the stitches 24 as the needle-bar 19 recedes. The heddles 9a now move in a lateral direction to the opposite hand, above explained, and descend to interlace the binder warps 16a with the main warps 15a, before the heddles 9a and loop-forming instrumentalities 10a move in a lateral direction to the other hand, as also above explained, for descent to form a new shed S^a while the comb 21 recedes and beats up again as aforesaid with resultant drawing of new loops 23 by the needles 22.

Referring now to Figs. XX-XXIIIa, which illustrate a still further manner and means for producing fabric in accordance with this invention, as previously indicated corresponding parts are designated by similar reference characters but in this instance having the exponent b. The characteristic distinction of this form of fabric F^b resides in the fact that one of the threads or yarns for convenience hereinafter termed the warp, is floated in one direction and interlaced with the other thread or yarn, for a like reason termed the weft, in the reverse direction.

Assuming that the various cooperating instrumentalities occupy the position shown in Figs. XX and XXa; that is to say the respective parts are ready for the front motion, with the several warp threads or yarns 15b individually-threaded, from supply, through the slots 25 of a jacquard controlled guide-bar 26; and the respective weft threads or yarns 17b, likewise from supply, through the guide eyes 11b of the heddle-fingers 9b, said warps 15b are moved two gaits to the left-hand, as indicated by the dot-and-dash lines in Fig. XXa, when the front comb 27 is suitably moved upwards over the rectilinear path indicated at P, Fig. XX to beat up floats f of the thread or yarn warps 15b to the position shown in Figs. XXI and XXIa, or in front of the fabric F^b. The hook bar 28 next elevates and the hooks 29 thereof pierce the previously-formed loops 24b of the fabric F^b, and engage the weft threads or yarns 17b on the side of the heddle-fingers 9b nearest said fabric, as indicated in Figs. XXI and XXIa, whereupon new loops 23b are drawn to the front of the fabric F^b, as shown in Figs. XXII and XXIIa, as the hook-bar 28 partially recedes. The rear comb 30 thereupon moves downwardly over the curvilinear path P', indicated in Fig. XXII to its lowest position, when the warps 15b are moved two gaits to the right-hand, or from the dot-and-dash line position to the full line position in said figure, which transfers or places the warps 15b to the back of the new or interlacing loops 23b, as will be fully understood on an inspection of Figs. XXII and XXIIa. The rear comb 30 is now moved forwards over the rectangular course marked P² to beat up new interlacing warps 31, or to the position of Figs. XXIII and XXIIIa. As the hooks 29 of the hook-bar 28 now swing rearwards through the gaits formed by the warps 15b, or towards the back of the fabric F^b, where they hold the loops 23b in position for penetration by the heddle-fingers 9b feeding-in the interlacing thread or yarn wefts 17b for completion of the stitches 24b, in an obvious manner.

To complete the cycle, the hook-bar 28 next swings forwardly, to release the stitches 24b for retention by the heddle-fingers 3b and descends, followed by the front comb 27 which now traverses the curvilinear path marked P³ in Fig. XXX, or to its lowermost position. Obviously, the guide bars 26 may be moved at the front or back motion any desired number of gaits, limited only by the gage of the various doppers of the 10 jacquard, not shown, in either direction. Furthermore, the number of guide bars 26 used may also vary from one upwards to any desired extent depending on the design of the machine to which the invention is applied. Still further, 15 it will be readily appreciated, by those conversant with the art, that the just described form of this invention covers the production of a double-action fabric, or one in which there are two motions for each point of interlacing L^b. 20 In other words, the warps 15b are tied-in before all the odd motions such as 1, 3, 5, etc., when moved in direction; while they will not tie-in before the even motions 2, 4, 6, etc., whether moved or not moved. Also, the warps 15b can 25 float when moved on the front motion, as well as when they remain in their respective gaits on the back motion.

Referring now to Figs. XXIV-XXVa, inclusive, which depict another modified means for the 30 production of fabric in which interlacings are effected with each motion or in both directions, corresponding parts are, as previously, designated by the same reference characters, but with the added exponent c. The fabric F^c supporting bed or beam 18c is provided with stepped-projections 32 having inclined notchings 33 for purposes later on understood, while a reciprocative needle bar 19c having spring-beard needles 34 is included in the cooperating instrumentalities 35 shown. In this single-action method, or further modified form of the invention, the fabric F^c is formed by the warps 15c being moved laterally, as before described, whereupon the spring-beard needles 34 are moved through the gaits 40 formed incident to elevation of either comb 27c or 30c, after each movement of the guide bar 26c. The spring-beard needles 34 then engage the weft or interlacing threads or yarns 17c, in front of the warps 15c, to draw fresh loops 45 23c, Fig. XXV, in the manner hereinbefore set forth, to effect tying-in or completion of the interlacings L^c. Otherwise the various moves and motions are the same as described in connection with Figs. XX-XXIIIa, excepting that the warps 50 15c are not floated across the face of the fabric F^c.

Referring now to Figs. XXVI-XXX, inclusive, which illustrate still another modified means suitable for producing a double-chain stitch 55 60 of the weft threads or yarns 17d for interlacing by the warps 15d, it is to be noted there are employed two, or front and rear, needle-bars 36, 37, respectively, having latch needles 38, 39; opposing weft thread or yarn stationary guide-bars 65 40, 40'; and vertically-movable front and rear combs 41, 42, having their upper portions 43, 44, respectively, bent towards each other at right-angles relative to their main finger or shank portions. In this single-action two-needle type of 70 the invention, the newly formed loops 23d must be transferred, for example, from the front needles 38, Fig. XXVII, to the rear needles 39, Fig. XXVIII, before lateral movement of the guide-bar 26d and incident beating-up of the warps 75 15d by the front comb 43, Fig. XXIX; or vice

versa. The needles 39 of the rear needle bar 37 upon forward movement engage the front wefts 17d to draw new loops 23d, as shown by dot-and-dash lines in Fig. XXIX, whereupon the rear comb 42 descends, Fig. XXX, in readiness for 5 subsequent beating-up of fresh warps 15d. After the loops 23d have been transferred to the front needles 38, the following motions of the various parts, to complete the knit-weave cycle, are 10 similar but opposed relative to those above described, with respect to the fabric F^d, in connection with the rear wefts 17d. In other words, in the single-action two-needle type of effecting a 15 knit-weave as just described one needle-bar moves from the rear, for example, through the various gaits of the associated comb after the motions of the different warps effected by their 20 guide bar, and engages the interlacings or wefts from the front; and the other needle-bar moves from the front, for example, through the various gaits formed, as before, and engages the interlacings or wefts from the rear or vice versa.

From the foregoing, and without further elaboration, it is thought the gist of the invention, as 25 well as its advantages, will be clearly apparent so that others may, by applying current knowledge, readily vary the same for embodiment in different machines adapted to the production of lace, porous or similar net fabrics, without eliminating 30 certain characteristic features that may be properly said constitute the essential items of novelty involved, which items I intend to be defined and secured to me by the following claims.

Having thus described my invention, I claim:

1. The method of producing a net fabric which 35 consists in throwing a weft thread across a plurality of warp threads incident to lateral movement of the latter, and forming complete twists in one motion by interlacing alternate warp threads with the other warp and weft threads at 40 the crossover points.

2. The method of producing a net fabric which 45 consists in throwing a weft thread back and forth through a plurality of warp threads incident to lateral movement and shedding of the latter, and forming complete twists in one motion by interlacing alternate warp threads with the other warp threads and said weft thread at the crossover points.

3. The method of producing a net fabric which 50 consists in throwing a weft thread back and forth through a plurality of warp threads incident to lateral movement and shedding of the latter, and interlacing said threads in one motion by twisting alternate warps over the other warps as well as under and over the weft thread at the crossover points.

4. The method of producing a net fabric which 55 consists in throwing a weft thread across alternating main and binder warp threads and interlacing said threads in one motion by twisting the binder warps over the main warps as well as under and over the weft thread at the crossover points of such main warp and weft threads.

5. The method of producing a net fabric which 60 consists in throwing a weft thread through alternating main and binder warp threads incident to lateral movement of said binder warp threads a predetermined extent in continuously-reversing 65 directions with shedding of said warp threads, 70 and interlacing such weft and main warp threads in one motion by twisting the binder warps over said main warps as well as over and under the weft thread at the crossover points of such main 75 and weft threads.

6. The method of producing a net fabric which consists in throwing a weft thread through alternating main and binder warp threads incident to lateral movement of the binder warp threads 5 one gait in successively-reversing directions with attendant shedding of said warps, and interlacing the main warp and weft threads in one motion by twisting the binder warp threads over the main warp threads as well as over and under the 10 weft thread at the crossover points of such main and weft threads.

7. The method of producing a net fabric which consists in throwing a weft thread across a plurality of warp threads incident to lateral movement of alternate warp threads with attendant 15 shedding thereof, and interlacing said warp threads in one motion with the weft thread at their crossover points incident to continuous chain stitching of the one warp thread and looping 20 therewith of the other.

8. The method of producing a net fabric which consists in throwing a weft thread across alternating main and binder warp threads incident to lateral movement of said binder warp threads 25 with attendant shedding thereof, and interlacing the main and binder warp threads in one motion with the weft thread at their crossover points by continuous chain stitching of the main 30 warp threads and interlooping therewith of the binder warp threads.

9. The method of producing a net fabric, which consists in throwing a weft thread across alternating main and binder warp threads incident to lateral movement of the binder warp threads with 35 attendant shedding thereof, and interlacing said main and binder warp threads with the weft thread by continuous chain stitching of the main warp thread, and by twisting the binder warp threads over the main warp threads as well as under, over and under the weft threads, and looping 40 said binder threads through the chain stitches.

10. The method of producing a net fabric which consists in throwing a weft thread across alternating main and binder warp threads incident to 45 lateral movement of the binder warp threads in a predetermined direction and extent with attendant shedding thereof, and interlacing said main and binder warp threads with the weft thread by continuous chain stitching of the main 50 warp thread, by twisting the binder warp threads over the main warp threads as well as under, over and under the weft threads at their crossover points, and by looping the binder thread continuously through the chain stitched main warp 55 thread both at the crossover points aforesaid as well as through any intervening stitches determined by the gait of the warp threads.

11. The method of producing a fabric which consists in throwing plural threads laterally and 60 beating them up to form floats, drawing new loops to one face of the fabric from intervening threads through previously-formed stitches thereof and casting said stitches, throwing the plural threads laterally in the next motion to effect their placement at the back of the newly drawn loops aforesaid, beating-up the just thrown threads to effect 65 interlacing of the plural and intervening threads, and then returning the loops to the other face of the fabric to complete the cycle.

12. The method of producing a fabric which 70 consists in throwing plural warp threads laterally and beating them up to form floats, drawing new loops to the front of the fabric from plural weft threads through previously-formed stitches 75 thereof and casting said stitches, throwing the

plural warp threads laterally in the next motion to effect placement thereof at the back of the newly drawn loops aforesaid, again beating up the warp threads to effect interlacing of the warp and weft threads, and then returning said loops to the rear of the fabric to complete the cycle. 5

13. The method of producing a fabric which consists in throwing plural warp threads laterally and beating them up to form floats, drawing new loops at right-angles toward one face of the fabric from intervening warp threads through previously-formed chain stitches thereof and casting the latter, again throwing the plural warp threads laterally in the next motion to effect their placement at the back of the newly drawn loops, beating-up the last mentioned thrown threads to effect interlacing of the respective threads at their crossover points, and then returning the loops aforesaid to the other face of the fabric. 10 15

14. The method of producing a fabric which 20 consists in throwing a weft thread across alternating main and interlacing warp threads incident to lateral movement of the interlacing warps to form floats, drawing new loops to the front of the fabric from the main warp threads through previously-formed chain stitches thereof and casting the latter, again throwing the interlacing warp threads laterally in the next motion to effect their placement at the back of the newly-drawn loops 25 and beating them up to effect tieing-in of said interlacing warp threads at the crossover points 30 of the main warp threads and the weft thread, and pushing said loops to the back of the fabric to complete the cycle.

15. The method of producing a fabric which 35 consists in throwing plural main warp threads laterally a predetermined extent and beating-up the same to form floats across one face of the fabric, drawing new loops from plural interlacing threads through previously-formed stitches there- 40 of held toward the face of the fabric and casting said stitches, throwing the plural main warp threads laterally a corresponding extent to effect placement of the main threads at the back of the newly drawn loops, and beating them up to tie-in 45 said main and interlacing threads, and then returning the loops aforesaid to the rear of the fabric to complete the cycle.

16. The method of producing a fabric which 50 consists in throwing plural main warps laterally a predetermined extent and beating-up the same to form floats across one face of the fabric, drawing new loops from alternately-arranged interlacing warps through previously-formed stitches thereof held toward the face of the fabric and casting said stitches, throwing the main warps laterally in a reverse direction a corresponding 55 extent to effect placement of the main warp floats at the back of the newly drawn loops and beating them up to tie-in said main and interlacing warps, 60 and then pushing the loops aforesaid rearwardly to complete the cycle.

17. The method of producing a fabric which 65 consists in throwing main warp threads laterally a predetermined extent and beating them up to constantly form floats thereof across one face of the fabric, drawing new loops from intermediate interlacing threads through previously-formed stitches thereof at an angle toward the face of the fabric and casting said stitches, again throwing the main warp threads laterally a corresponding extent to effect placement of the main warp threads at the back of the newly drawn loops and beating them up to tie-in said main and interlacing warps, and then pushing the loops afore- 70 75

said to the back of the fabric to complete the cycle.

18. The method of producing a fabric from main and interlacing warp threads by lateral throwing of certain main warps a predetermined extent to form floats thereof; beating up said main warps, drawing new loops to the front of the fabric from interlacing warp threads through previously formed stitches thereof and casting 10 said stitches, beating-up certain warp threads laterally thrown a predetermined extent to effect interlacing of the warp threads and said certain main warp threads only, allowing other warp threads to float a certain number of motions, 15 and returning said loops to the rear of the fabric to complete the cycle.

19. The method of producing a fabric which consists in throwing main threads laterally a predetermined extent in constantly-reversing directions and beating-up said main threads to 20 form loops, drawing new loops from interlacing threads through previously-formed chain stitches thereof held on loop-drawing instrumentalities incident to each lateral throw of the main warp 25 threads and casting of the stitches aforesaid, whereby said main threads are interlaced through the consecutive stitches formed of the interlacing threads.

20. The method of producing a fabric which 30 consists in throwing plural main threads laterally a predetermined extent in constantly-reversing directions and beating-up said main threads to form floats, drawing new loops from plural interlacing threads through previously-formed chain 35 stitches held on the loop-drawing instrumentalities after each lateral throw of the main threads and casting of the stitches aforesaid, whereby the main threads are looped twice through the consecutive stitches formed of the 40 interlacing threads.

21. The method of producing a fabric which 45 consists in throwing plural main threads laterally a predetermined extent in constantly-reversing directions and beating-up said main threads to form gaits, drawing new loops in one direction from opposingly-fed interlacing threads through previously-formed loops held on suitable instrumentalities, transferring said new loops to an opposed set of such instrumentalities before the 50 succeeding lateral throw of the main threads, and beating-up new gaits with attendant drawing of fresh loops from the opposingly-fed interlacing threads and casting of those previously formed, whereby the main warp threads are looped 55 through double-chain interlacing stitches incidental to each lateral throw of the main threads.

22. The method of producing a fabric which 60 consists in throwing plural main threads laterally a predetermined extent in constantly-reversing directions and beating-up said main threads to form gaits, feeding-in opposed sets of interlacing threads and drawing new loops from the one set toward the back of the fabric, by suitable instrumentalities, through previously formed 65 loops, of the opposing set of interlacing threads, held thereon, transferring said new loops to an opposed set of such instrumentalities before the succeeding lateral throw of the main threads, and 70 beating-up new main thread gaits, with attendant drawing of fresh loops from the opposing set of interlacing threads toward the front of the fabric, and casting of the first-mentioned new loops, whereby the main threads are looped 75 through double-chain interlacing thread stitches

incidental to each lateral throw of the warp threads.

23. The method of producing net fabric which comprises throwing a weft thread across a plurality of warp threads and forming complete twists in alternate warp threads about the weft at the points of intersection of the latter with the remaining warps, with each such alternate warp passing under and over the weft at one side of the adjacent warp, and under the weft at the opposite side of said adjacent warp.

24. The method of producing a net fabric which comprises moving longitudinal warp and weft threads laterally in predetermined manner, beating-up the laterally moved threads to form shedways, at right angles with respect to the width of the fabric, for loops to be drawn through previously formed loops from interlacing warps on the opposite side of the fabric.

25. A method in accordance with claim 24 20 wherein predetermined warp threads form a transverse shedway of one or more complete cycles of twists around one lateral motion of the weft thread.

26. A method in accordance with claim 24 25 wherein certain warp threads form a transverse shedway of loops for a weft thread to pass through and twist under, and over and under the weft thread at one throw of said weft thread across the width of the fabric.

27. In means for producing net fabric including weft throwing means and beat-up mechanism, the combination of stationary main-warp guide-fingers with intervening loop-forming instrumentalities, each said finger having a guide-eye and notched free end, and reciprocatory bars one of which carries binder-warp guide-fingers and the other has loop-drawing instrumentalities with intervening combing elements; each last mentioned finger having a guide-eye, the loop drawing instrumentalities being notched at their termini, and the combing elements having cut-away free ends.

28. In means for producing net fabric including a weft throwing means and a reed; the combination of a stationary member having projecting guide-fingers for main warps with intervening loop-forming instrumentalities, said fingers each having a guide-eye and notched free end, and parallel reciprocatory bars one of which 50 affords support for binder-warp guide-fingers and the other similarly supporting notch-ended loop-drawing fingers with intervening combing elements having concaved free ends.

29. The combination of claim 28 wherein the 55 main warp guide fingers are horizontally disposed, and the parallel bars for guiding and drawing loops of the binder warps are vertically reciprocable to effect interlacing of said binder warps with the main warps at the crossover points 60 of the weft.

30. In means for producing net fabric including a weft throwing means and a reed, the combination of a stationary member having projecting guide-fingers for main warps with intervening loop-forming instrumentalities, said fingers each having a guide-eye and notched free end, parallel reciprocatory bars one of which supports binder-warp guide fingers and the other notch-ended loop-drawing fingers, a stationary sinker 65 bar, a movable comb, and a needle bar effective to continuously chain stitch the main warps over the interlacing points of the binder warps and wefts.

31. In jacquard controlled means for produc- 75

ing fabric the combination of reciprocable guide members for the warps, movable members having guide fingers for the wefts, a movable loop-drawing hook-bar for drawing loops of said wefts, and relatively movable point bars, whereby the warps are floated in one lateral motion and interlaced with the wefts in the other lateral motion.

32. In jacquard controlled means for producing fabric the combination of reciprocable guide members for the warps, movable members having guide fingers for the wefts, a movable needle bar for continuously chain stitching the wefts, relatively movable point bars, and means whereby the guide members, needle bar and point bars are respectively operated to interlace the warps and wefts incident to each lateral motion of the warps.

33. In jacquard controlled means for producing fabric the combination of reciprocable guide members for the warps; opposingly related stationary guide means for plural wefts, relatively movable point bars, opposed intermittently-operative needle bars, and means whereby the guide members, point bars and needle bars are operated to interlace the warps with double-chain stitching of the plural wefts.

34. The combination of claim 33 wherein the respective needle bars operate from back to front, and vice versa, with respect to the fabric.

35. The combination of claim 33, wherein the relatively-movable point bars have their finger free portions bent at right-angles towards each other with respect to their shanks.

OSKAR SAUER.
